UNITED STATES PATENT OFFICE.

JAMES F. McELROY, OF ALBANY, NEW YORK, ASSIGNOR TO CONSOLIDATED CAR HEATING COMPANY, OF ALBANY, NEW YORK, A CORPORATION OF WEST VIRGINIA.

HOSE-COUPING.

No. 805,744.

Specification of Letters Patent.

Patented Nov. 28, 1905.

Application filed March 19, 1904. Serial No. 198,895.

To all whom it may concern:

Be it known that I, JAMES F. McELROY, a citizen of the United States, residing at Albany, county of Albany, and State of New York, have invented certain new and useful Improvements in Hose-Couplers, of which the following specification and accompanying drawings disclose, as an illustration, one embodiment thereof which I now regard as the best out of the various forms in which the principles of the invention may be applied.

In the drawings, Figure 1 is a side elevation. Fig. 2 is a plan. Fig. 3 is a front end elevation.

My invention relates to hose-couplers for use in the steam heating of railway-vehicles, and is of the type wherein the coupler is made in two complementary parts, each provided with a projecting side wing adapted to overlap and engage with the other part.

It relates in particular to a coupler of that type wherein a supplementary spring-latch is employed to secure a more reliable engagement of the two parts without, however, preventing their disengagement when sufficient force is applied to draw them apart; and it consists in a spring-latch pivoted or otherwise mounted on one part and also mounted on the nozzle portion of the coupler which lies back of the body portion and is separable therefrom. By this means a new body portion may be applied without disturbing the latch and without the need of a new latch. In existing couplers also unprovided with a latch it will only be necessary to provide a new nozzle portion with the latch mounted therein instead of providing a wholly new coupler.

Referring to the drawings, A represents the body portion of one half of a coupler from which projects forwardly the side wing B to overlap and engage with the complementary half of the coupler in a well-known manner. The body A also carries the usual packing-gasket.

Back of the body portion A is the nozzle portion C, having on one side the hose-nozzle G projecting therefrom and on the other side having the separable body portion A, secured thereto by bolts *a a*. On the nozzle portion C is mounted a latch D, which is pivoted thereto on a vertical pin E, which passes through an opening in the latch that is con-

ical or enlarged on its under side and is then passed down through the part C and is surrounded by a spring F, which draws downward on the pin, and hence on the latch. The head of the pin bears on the peak of a ridge on the upper side of the latch, and by reason of this feature and the enlargement of the hole in the latch the latch may be lifted at its outer end and moved vertically a limited distance against the force of the spring F. In this movement the latch practically turns on its rear lower edge as a center. The normal or engaging position of the latch is that shown in Figs. 2 and 3, wherein it is represented as extending forwardly and parallel to the axis of the coupler, but at one side of the body portion A and over the place occupied by the wing of the adjacent half of the coupler when the two halves are engaged with each other. The latch may, however, be turned by hand outwardly away from the body A around the pin E as a center, so as to be out of the way of the coupler-wing. It will be necessary to thus turn the latch when the halves are coupled together and then turn it back into the position shown in Figs. 2 and 3 after the two halves are in place, or it may be left in its turned-out position if it is not to be used. When, however, the two halves are to be uncoupled by turning them in the well-known way around the lower edges of their meeting faces as a center, then the wings will tend to lift the outer ends of the latches against the face of their retaining-springs F, and the springs will be of such strength as to yield and allow the latches to lift and permit the escape of the wings therefrom. It will also be observed that, if desired, the under side of the projecting portion of the latch may be slightly inclined downward below the level of the upper edge of the part on which the latch is seated. Then if the upper side of the engaging wing lies on the level of said seat the outer end of the latch will be slightly lifted when in position on the top of the wing and so cause the spring to exert a positive depressing effect on the wing, tending to make it engage more firmly with the lug on the body, into which it takes in a well-known way. The latch will be held in either of its two positions by a lug on the under side of its rear projection that is adapted to drop into one or the other of two shallow pits *d' or d''* on

the upper surface of the seat on which the latch rests. While this is the preferred form of latch, other forms may be substituted. Since the latch is mounted on the nozzle portion C, it is independent of any removal of the body portion A, with the results already mentioned.

I do not herein claim, broadly, the idea of an automatically-releasing spring-latch pivoted to swing into and out of a position overhanging the complementary coupler part, as this is made the subject of a separate application, Serial No. 198,285.

What I claim as new, and desire to secure by Letters Patent, is—

1. A hose-coupler half comprising a body portion formed with a gasket - face, a forwardly-projecting wing adapted to interlock with the complementary coupler half, and a lug adapted to interlock with the wing of said complementary half, a nozzle portion separably connected with said body portion, and a supplementary latch mounted on said nozzle portion and adapted to engage the complementary coupler half.

2. The combination with a coupler half,

having separable nozzle and body portions, the latter provided with a forwardly - projecting side wing to overlap and engage with a similar complementary half, of a supplementary spring-latch mounted on the nozzle portion and adapted to engage with the complementary part when said part is in its interlocking position.

3. The combination with a coupler half, having a side wing to overlap and engage a complementary half and also provided with separable nozzle and body portions, of a pivoted latch mounted on the nozzle portion but adapted to be turned inwardly to overhang the complementary half when in its interlocking position, and a spring serving to retain the latch but adapted to yield to permit the uncoupling of the two halves.

In witness whereof I have hereunto set my hand, before two subscribing witnesses, this 16th day of March, 1904.

JAMES F. McELROY.
